UNITED STATES PATENT OFFICE

2,332,033

CONTROL FOR RECORD SUPPORTING MEANS

J Willard Welker, Dayton, Ohio, assignor to The National Cash Register Company, Dayton, Ohio, a corporation of Maryland

Application February 26, 1941, Serial No. 380,706

16 Claims. (Cl. 197—127)

This invention pertains to record material supporting means of the "front-feed" type in which the supporting means normally is in closed-throat position, where it retains the record material in printing position, but is shiftable to an open-throat position, where certain elements of the supporting means are moved to release the record material and form an open throat or guiding passage to permit the ready insertion and removal of said record material from the front of the machine. In particular, the invention is concerned with the provision of novel control means and electromagnetic actuating means for shifting the record material supporting means.

In prior art machines employing the "front-feed" type of record material supporting means, the shifting of the supporting means to open-throat position required some form of control utilizing the movement of the supporting means to a columnar position or the location of the supporting means in a particular columnar position, or, in lieu of these controls, some manipulative device had to be operated to initiate a throat-opening operation.

All of the prior art requirements and limitations on the control of the throat-opening operations are eliminated in applicant's novel arrangement, in which a source of radiant energy and a detector of such energy are so located in front of the record material supporting means that a beam of radiant energy extends across the machine where the hand of the operator, in moving toward the record material to remove said material, will interrupt the beam, and a circuit controlled by the detector and including the electromagnetic actuator will be completed and cause the actuating means to move the record material supporting means to open-throat position quietly and quickly. In the instant embodiment of the invention, the source of radiant energy is a light source, the detector is a photo-electric cell, and the actuating means comprises an electromagnet in a circuit controlled by said cell.

The novel control means and actuating means are particularly useful when used in connection with a record material supporting means supported by a traveling carriage, because their operation is in no manner dependent upon any carriage movement or position nor upon any particular operation of the accounting machine. This condition enables one or more printing operations to be performed in any one or more columns of a record material without causing the supporting means to be shifted to open-throat position, 55

which is not possible when the carriage movement or position is used to control the shifting means. After the desired number of printing operations on the record material, the operator merely reaches for the record material to remove it from the machine, and the actuating magnet is energized to shift the supporting means to open-throat condition, regardless of the position of the traveling carriage.

10 Accordingly, it is clear that, when the novel control means and actuating means are used, the operator does not have to make any adjustments of tappets or control elements or operate any keys or manipulative devices; all that is necessary is that the operator perform the natural operation of reaching for the record material, and the electromagnet is operated to shift the supporting means to open-throat position to release the material so that it may be removed from the machine. The improved control means and actuating means, therefore, simplify the operation of the machine by the operator, inasmuch as they require no particular effort on the part of the operator and no special operations of parts or sequence of operations to be remembered by the operator.

Control means are provided to prevent repeated operations of the actuating electromagnet when the record material supporting means is in open-throat position and the beam of light is interrupted, as would be the case when a new sheet of record material was being inserted following the shifting of the supporting means to permit the removal of another previously-inserted sheet.

35 Additional control means are provided to delay the operation of the electromagnetic actuating means if the beam of light is interrupted during an accounting machine operation before printing has taken place. This will prevent the record material from being shifted out of printing position before an impression can be made thereon.

40 Retaining means are provided to cause a circuit for the actuating electromagnet, which circuit is closed when the beam of light is blocked from the photo-electric cell, to remain closed until the actuating electromagnet is operated, even though the light is no longer blocked from said cell.

45 It is, therefore, an object of this invention to provide an electromagnetically-operated actuating means for causing a "front-feed" type of record material supporting means to be shifted.

Another object of the invention is the provision of a novel actuating means for shifting a record material supporting means, said actuating

means deriving no control or power from the operation of the machine with which the supporting means is associated.

Another object of the invention is the provision of an electromagnetic operating means controlled by a photo-electric control means for shifting a "front-feed" type of record material supporting means from closed-throat position to open-throat position.

Another object of the invention is to provide an electromagnetically-operated actuating mechanism for shifting a record material supporting means, which actuating mechanism is simple in construction, fast in operation, and controlled by a photo-electric control means with the minimum of effort on the part of an operator of the machine with which the supporting means is used.

Another object of the invention is to provide a photo-electrically-controlled electromagnetically-operated actuating means for shifting a record material supporting means to open-throat position and to provide controls to delay and prevent the operation of the actuating means under conditions which would result in an improper operation or an idle operation of the actuating means.

Another object of the invention is to provide a photo-electrically-controlled electromagnetically-operated actuating means for shifting a record material supporting means to open-throat position, and means to delay the operation of the actuating means if the photo-electric control would be rendered effective and tend to cause an operation of the actuating means before recording on the record material is finished.

Another object of the invention is to provide a novel actuating means operated to shift a record material supporting means when a circuit is closed under control of a photo-electric cell as the status of the light on the cell is changed, and means to maintain the circuit closed even after the status of the light on the photo-electric cell is restored.

Another object of the invention is to provide an electromagnetically-operated actuating means rendered operable under control of a photo-electric cell for shifting a record material supporting means, and means for preventing an operation of the actuating means, when the supporting means has been shifted, to avoid idle operations of the actuating means.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a side elevation, as observed from the right, showing the shifting mechanism for the record material supporting means and the relative positions of the parts of such mechanism when the supporting means is in closed-throat or printing position.

Fig. 2 is a side elevation, as observed from the right, showing the shifting mechanism for the record material supporting means with the various parts in the positions which they assume when the supporting means is in open-throat position.

GENERAL DESCRIPTION

The "front-feed" type of record material supporting means is used where it is desired to insert 40 and remove individual record sheets into and from the front of the machine.

One use of this type of supporting means may be found in a bank where an individual ledger sheet is provided for each depositor, upon which 45 ledger sheet a record of the daily balancing of his account is printed. Under these circumstances, large numbers of ledger sheets must be inserted into and removed from the machine each day. It is necessary, therefore, that means 50 be provided whereby the ledger sheets may be quickly inserted into the machine, located at the proper printing line, and, after the balancing operation is completed, quickly removed from the machine with the least amount of effort on the 55 part of the operator.

To accomplish this, in the present embodiment, the record material supporting means is shiftable from closed-throat or printing position to open-throat position and vice versa and comprises a 60 platen, pressure rollers, a work table, and guide plates mounted in a frame for shifting movement. When the supporting means is in printing position, the platen is adjacent the printing means, and the pressure rollers engage the ledger 65 sheet with the platen to retain the ledger sheet against movement during a printing operation.

After the printing operation or operations have been completed and it is desired to remove the ledger sheet from the machine, the operator 70 merely reaches for the ledger sheet, and, in so doing, his hand interrupts a beam of light, which causes an electromagnet to function. The electromagnet operates a linkage to shift the platen from printing position to a more accessible position and move the pressure rollers to a position 75

where they, together with the platen, the work table, and the guide plates, form a throat or guide chute to make the removal of the ledger sheet very easy.

A new ledger sheet may then be inserted into the record material supporting means, which can then be shifted manually to printing position, and the operation can be repeated.

It will be clear from the following detailed description that this arrangement requires no setting of control elements or manipulation of control keys, no power derived from the accounting machine, and no previous operations of the accounting machine, nor does it require any particular effort on the part of the operator to cause the record material supporting means to be moved to open-throat position.

Various control means are provided to prevent the operation of the actuating electromagnet when the supporting means are already in open-throat position or during a certain part of an operation of the accounting machine.

A journal sheet and superimposed carbon paper are usually used to make a record of the transactions recorded on the ledger sheets, and this journal sheet and carbon paper are held on the platen by sets of additional pressure rollers, which are not released by the movement of the record material supporting means to open-throat position. A manually-operable member can be operated to release these pressure rollers when it is desired to remove the journal sheet from the machine.

In the instant embodiment, which shows the record material supporting means mounted in a laterally shiftable traveling carriage associated with a well-known form of accounting machine, the source of light and the photo-electric cell are so located that a beam of light extending from the light source to the photo-electric cell can be broken by the hand of the operator in reaching for the record material in any of the positions to which the traveling carriage may be shifted laterally, and the actuating means can respond to the control in any position of the carriage. It is obvious that applicant's novel control means and actuating means can be used with a record material supporting means which has no lateral shifting movement, since the control and actuation are in no way dependent upon any lateral shifting of the supporting means. Furthermore, the record material supporting means is shown associated with an accounting machine, but, since the actuating means for shifting the supporting means derives no power from nor is dependent upon any operation of the machine, the supporting means and the actuating means could equally well be used with any other machine in which a front feed of record material is desired.

DETAILED DESCRIPTION

Accounting machine

The invention is shown as being used with an accounting machine to control the shifting of the "front-feed" type of record material supporting means. As the type of accounting machine shown in Fig. 6 is well known and is illustrated and disclosed in the United States Patents No. 2,038,717, which issued to Raymond A. Christian on April 28, 1936, and No. 2,082,098, which issued to Raymond A. Christian on June 1, 1937, only those details of the accounting machine which are necessary to an understanding of the invention will be described herein.

The various mechanisms of the accounting ma-

chine are supported by side frames as 61 (Fig. 1) and cross frames as 62 and 63 (Fig. 9).

A cabinet 64 (Fig. 6), which supports a carriage front guide rail and a carriage rear guide rail 68, encloses the machine, which has at the front thereof the usual rows of amount keys 67 and control keys 68.

A traveling carriage (Fig. 6), formed with two connected side members 69 and 70, which carry the various record material supporting means, is laterally shiftable on the guide rails 65 and 66. The lateral shifting of the carriage is used to bring various portions of the record material opposite a set of printing elements 71, from which amounts or other data may be printed.

The manner in which the lateral shifting of the carriage is brought about and the manner of controlling the positioning of the printing elements is clearly explained in the above-mentioned Christian Patent No. 2,082,098, to which reference may be had for further details.

Associated with the accounting machine is a plate 72 (Fig. 10), which has a shaft 73 journaled therein, which shaft is driven one revolution counter-clockwise each time the accounting machine is operated.

Front-feed supporting means for record material

The record material supporting means which enables "front-feeding" operations to take place comprises a platen 74 (Figs. 3 and 4), lower pressure rollers 75, a lower work table 76, and side guides 77 (only one of which is shown). These parts, which are generally similar to those shown in the copending United States application Serial No. 653,838, filed on January 27, 1933, by Raymond A. Christian, can occupy a closed-throat position as shown in Fig. 3, where the platen 74 supports the record material in printing position and the pressure rollers 75 hold the material against movement, and also can be shifted to an open-throat position, as shown in Fig. 4, where the platen 74 is raised and the pressure rollers 75 are disengaged from the platen, so that these parts, together with the lower work table 76 and the side guides 77, form a chute or throat by means of which record material can readily be inserted into or removed from the front of the machine.

The various elements of the record material supporting means are carried by a rockable frame composed of side plates 80 and 81 connected together by the tie rods 82 and 83 and the cross bar 84. Secured in the carriage side members 69 and 70 and extending across the carriage is a rod 90 (Figs. 1 and 2), upon which are pivoted frame-supporting arms for rockably supporting the frame in the carriage. Frame-supporting arm 91 has its rear end bifurcated to engage a stud 92 in the side plate 80 and its forward end 93 hook-shaped to receive a platen-supporting shaft 94, which is journaled in the side plates 80 and 81. In a similar manner, another frame-supporting arm (not shown) is mounted on the rod 90 adjacent the side plate 81 and provides a means for supporting this side of the frame for rocking movement about the rod 90.

The manner in which the various elements of the record material supporting means are mounted in the rockable frame is shown in Figs. 1, 2, 3, 4, 6, 7, and 8 and will now be described.

The platen 74 is supported by the shaft 94, rotatably journaled in the side plates 80 and 81 of

the rockable frame. The lower sets of pressure rollers 75 are rotatably mounted on studs extending between sets of pressure roller carrying arms 95 loose on shaft 96 rockable in the side plates 80 and 81.

A set of stop arms 97 (Figs. 7 and 8) are carried by the shaft 96 and are adjustably connected therewith by means of the screws 98 and the arms 99 pinned to the shaft. A rod 100 fastened in the arms 97 extends through slots 101 in the pressure roller carrying arms 95 and enables the stop arms 97 to control the position of the pressure rollers 75 as well as their shifting from closed-throat position to open-throat position.

Encompassing the shaft 96 is a series of torsion springs 102 (Fig. 7), one end of each of said springs 102 engaging one of the arms 95 and the other end of each spring engaging a hole in an adjustable collar 103 retained in position on shaft 96 by a set screw. With the set screws loosened, the collars 103 are rotated clockwise about shaft 96, as viewed in Fig. 8, and, through the springs 102, urge the pressure roller carrying arms 95 clockwise, as viewed in Figs. 3, 4, and 8, until the lower part of the slots 101 yieldingly engage the rod 100 with the proper degree of pressure, after which the set screws are tightened to retain the collars 103 in their set positions. As the collars 103 and the stop arms 97 are both fastened to shaft 96, the pressure caused by the adjustment of the springs 102 will not be affected by the rocking of the shaft 96, and the pressure roller carrying arms 95 will move with the stop arms 97 from closed-throat position as shown in Fig. 3 to open-throat position as shown in Fig. 4, and vice versa.

The lower work table is fastened to the cross bar 84 of the rockable frame, which cross bar also supports the side guides 87, clamped thereon in any lateral position between the side plates 80 and 81 to control the lateral positioning of the record material. The front edge of the work table 76 is cut away opposite the pressure rollers 75 to allow the pressure rollers to contact the platen in closed-throat position, as shown in Fig. 3. When the lower work table 76 is in open-throat position, its forward edge moves upward to a position adjacent a line-finder and guide 104 mounted in brackets 105 and 106 secured to the carriage side members 69 and 70 respectively, and serves to guide the record material toward the rear of the machine.

Frame-rocking mechanism

The mechanism for rocking the frame in which the record material supporting means is carried is substantially the same as that shown and described in the above-mentioned application of Raymond A. Christian, Serial No. 655,838. Only the mechanism located adjacent the side plate 80 of the frame is shown in Figs. 1, 2, and 8 of the drawings, because it is believed that this is sufficient to enable an understanding to be had of the invention.

Secured in the carriage side member 69 is a stud 107, upon which is pivoted an arm 108. The upper end of arm 108 is bifurcated to receive a stud 110 secured on an arm 111 fast on a shaft 112 journaled in the side plates 80 and 81 of the rockable frame. Also fast to shaft 112 and adjacent the side plate 81 is an arm 123 (Fig. 8), which has a stud 124 engageable by the upper bifurcated end of an arm (not shown) similar to arm 108 but pivoted on a stud on the carriage side member 70. These arms, which are pivoted

on the carriage side members, have their lower ends connected by a rod 109 (Fig. 1). A spring 125 (Figs. 6 and 8), connected to the arm 123 and to the side plate 81, tends to move the shaft 112 in a clockwise direction as viewed in Figs. 1 and 8. The shaft 112 is prevented from moving clockwise at this time by means of a roller 113, carried by the arm 111, engaging the end of a link 114 pivoted on stud 115 on the side plate 80. The link 114 is held in the path of the roller 113, as shown in Fig. 1, by a stud 116 on a blocking member 117 loosely pivoted on the shaft 112 but prevented from turning thereon by the engagement of the end 118 of the blocking member 117 with the stud 119 in the carriage side member 80.

In the present embodiment, the frame is rocked by an operating means which engages the rod 109 and rocks the arm 108 clockwise about the stud 107. The upper bifurcated end of the arm 108 engaging the stud 110 tries to rock the arm 111 clockwise, but this is blocked by the link 114 being in the path of the roller 113. Since the shaft 112 and the arm 111 are prevented from rotating in the side plates, the movement of the bifurcated end of the arm 108 is transmitted to the side plate 80 through the shaft 112 and also through the link 114 and the stud 115, causing the frame, by means of the frame-supporting arm 81, to pivot clockwise about the rod 90. The end 118 of the blocking arm 117 has an inner surface 120, which is formed as an arc with the rod 90 as a center, so that, as the frame rocks about the rod 90, the blocking member 117 will continue to hold the link 114 in the path of the roller 113, and this condition will continue until the frame is moved to open-throat position and the notch 121 in the member 117 is opposite the stud 119. When the notch 121 is moved opposite the stud 119, the blocking member 117 is allowed to rotate a slight distance clockwise about shaft 112, and this will allow the link 114 to move from the path of the roller 113 and enable the arm 108 to operate the arm 111 to rock the shaft 112 clockwise in the side plates of the frame. The rocking of the arm 111 with the shaft 112 carries the roller 113 over the upper edge of the link 114 until it rests in the dwell 122. This causes the link 114 to bear on the stud 116 on the blocking member 117 and retain the notch 121 over the stud 119, which locks the frame in open-throat position.

Also fast on the shaft 112 are slotted arms, one of which is shown at 128 in Fig. 8, for rocking the shaft 96 to shift the pressure rollers 75. The operation of these arms is similar, so only one will be described.

In the lower part of arm 126 is a V-shaped slot 127, in which is a roller 128 carried by the arm 129 pinned to the shaft 96. In Fig. 8, the arm 126 is shown in open-throat position, to which it has been shifted by the shaft 112 moving clockwise, and the roller 128 has been shifted from the left-hand end of the slot 127, where it was located until the shaft 112 was rocked, to the right-hand end of the slot and has caused the arm 129 to rock the shaft 96 counter-clockwise and move the arms 97 and the rod 100 to shift the pressure rollers 75 away from the platen 74, or closed-throat position, as shown in Fig. 3, to the open-throat position, as shown in Figs. 4 and 8.

It is thus seen that the frame-rocking mechanism first rocks the frame and moves the platen from printing position to a more accessible position and moves the lower work tray to a position

to receive the record material when it is inserted from the front of the machine and thereafter shifts the pressure rollers to release the record material so that it may be readily inserted into or removed from the front of the machine.

A curved stop member 130 (Fig. 1) is fastened to the carriage side member 69 and, when the frame is rocked to open-throat position, coacts with a collar 131 carried by the shaft 94 to limit its upward movement. A second stop member 132, pivoted on the rod 90 and adjustable vertically by the eccentric 133, engages the collar 131 to arrest the frame in closed-throat position with the platen in proper relation to the printing mechanism. A similar pair of stops, not shown, are carried by the carriage side member 70 and serve to limit the movement of the other side of the rockable frame.

Manual means are provided to rock the frame and the front-feed supporting means thereon from open-throat position to closed-throat position. This means is shown in Figs. 1, 2, and 6 and will now be described.

Secured on the carriage side member 69 is a bracket 134, on which is pivoted a restoring lever 135 provided with a finger piece 136 and an extension 137 (Figs. 1 and 2). Pivoted to the extension 137 is a link 138 having a slot 139 adapted to cooperate with a stud 140 secured to the arm 111. When the frame is rocked clockwise from closed-throat or printing position to open-throat position, the stud 140 engages the end of the slot 139 in the link 138 and rocks the lever 135 clockwise until the lever engages a bumper 141 carried by the upper stop member 130.

To restore the frame and the front-feed record material supporting means to closed-throat or printing position, the finger piece 136 is struck by the operator, and this rocks the lever 135 counter-clockwise, which, through the link 138, the stud 140, and the arm 111, rocks the shaft 112 counter-clockwise to cause the arms as 126 to rock the shaft 96 to move the pressure rollers 75 into engagement with the platen 74 and to cause the roller 113 to be removed from locking engagement with the link 114. The release of link 114 allows the notch 121 in the blocking member 117 to leave the stud 119 and enables the frame to move toward closed-throat or printing position. The inertia of the frame and the parts supported thereon will cause the frame to continue to move to closed-throat position even after the restoring lever 135 is returned to normal position and the stud 140 has left the end of the slot 139.

Actuating means for the frame-rocking mechanism

The side frames of the accounting machine, one of which is shown schematically at 61 in Fig. 1, support a rockable shaft 142. An arm 143, fastened to the shaft, extends upwardly, so that it can engage the rod 109 in any position of the carriage and can pivot the arms, as 108, clockwise to rock the frame from closed-throat position to open-throat position, as explained above.

The shaft 142 (Fig. 1) also has fastened thereto an arm 144 connected to a link 145, which is operated by an actuating electromagnet 146 (Fig. 9).

The actuating electromagnet 146 and certain elements of the means for controlling its operation, shown in Figs. 9 to 12 inclusive, are carried by a bracket fastened to the cross frames as 63

and comprising a vertical plate 147 and a base plate 148.

The link 145 is connected to one arm 149 of a lever fastened to a shaft 150 rotatable in a U-shaped bracket 151 attached to the vertical plate 147. The other arm 152 of the lever is bifurcated to engage a pin 153 in the end of a core 154, which is operated by the magnet 146. A spring 155, attached to the arm 152 and to the vertical plate 147, urges the shaft 150 clockwise as viewed in Fig. 11 and operates through the lever 149—152, the link 145, the arm 144, and the shaft 142 to maintain the arm 143 in engagement with the rod 109 and to prevent an overthrow of the core 154 when the frame is restored to closed-throat position.

The actuating means for the frame-rocking mechanism, therefore, comprises an electromagnet having associated therewith a core which is pulled within the magnet when the magnet is energized. The core is connected to the arm 143 by a linkage and rocks the arm 143 counter-clockwise to shift the frame to open-throat position. When the frame is shifted manually to closed-throat position, the rod 109 shifts the arm 143 clockwise, and this arm, through said linkage, moves the core 154 from within the magnet and conditions the actuating means for further operations, as will be explained hereinafter.

Control means for the actuating means

The means for controlling the actuating means for the frame-rocking mechanism is most clearly shown in Figs. 6 and 9 to 12 and will now be described. In the instant embodiment, a tubular member 161, carried by the accounting machine cabinet 64, has its upper end bent over, so that it is located adjacent the traveling carriage. At the upper end of the tubular member 161 is an enlarged section 156 containing the source of radiant energy, which, in the instant embodiment, comprises a lamp 157 (Fig. 12) for directing a beam of light across the front of the machine at a point where the hand of the operator will pass when reaching toward the carriage to remove record material therefrom. Mounted on the machine in the path of the beam of light is another tubular member 158 containing a photo-electric cell 159 (Figs. 1 and 12), which is included in a circuit taken by a cable 160 to the control means carried by the bracket 147, so that the photo-electric cell can control the operation of the link 145 by the actuating electromagnet 146. The cable 160 is a low-capacity cable which is grounded to stabilize the control exerted by the photo-electric cell.

With the light-source-carrying section 156 and the tubular member 158 located as shown in Figs. 1 and 6, it is obvious that the hand of the operator in moving toward the record material will block the beam of light from the photo-electric cell and cause the control circuits to function. In the control circuits shown in Fig. 12, the photo-electric cell 159 is included in a circuit to which a grid 166 of a gas discharge tube 167 is connected to enable the photo-electric cell to control the conductivity of said tube. When said tube is conductive, it causes a relay 168 connected in the plate circuit of said tube to be energized to close a circuit to the actuating electromagnet 146. The manner in which the control circuits operate will now be explained.

A transformer 169 has its primary winding connected across the main power supply lines 170, 171 and its secondary tapped at points 172,

173, 174, 175, 176, and 178 to provide the required voltages for the various elements of the control means. The photo-electric cell 159 and a variable capacitor 178 are connected in a balanced circuit extending from the point 172 to the point 174, in which circuit the capacitor 178 can be adjusted so that, with the photo-electric cell conducting, the potential of the point 180, where the grid 166 is connected in the circuit, and the grid 168 will be less positive than the point 173 when point 174 is positive. The cathode 181 is connected directly to the point 173, and the plate 182 is connected through the relay 168 to the point 174. The discharge tube 167 is of the grid-controlled type that will discharge when the potential of the plate is positive with respect to the cathode and the potential of the grid is more positive than a critical value relative to the cathode 181.

When the beam of light is on the photo-electric cell and the cell is conducting, the grid 166 will have a potential less positive than said critical potential, while the plate 182 has a positive potential thereon, and the tube will not be conductive, so that control relay 168 will not be energized. The blocking of the light from the photo-electric cell 159 will cause the impedance of the cell to increase and will cause the potential of the grid 166 to become more positive than said critical potential while the plate 182 is positive, and the tube 167 will fire and be conductive. The current in the plate circuit will cause the relay 168 to be energized and operate a switch 183 to complete a circuit to the actuating magnet 146, under proper circumstances which will be explained later herein. The circuit completed by the switch 183 can be traced from the main supply line at point 170; through the line 184; actuating electromagnet 146; the switch 185, which is closed whenever the supporting means are in closed-throat position; the switch 183; line 186; the switch 187, which is closed when the accounting machine is not being operated; and line 188 to the main supply line at point 171.

Potential is applied to the heater filament of the tube 167 by connecting the filament across the points 175 and 176 of the transformer. The potential for operating the lamp 167 is obtained by connecting the lamp across the points 175 and 178 of the transformer.

The various control elements and the means for insuring that they will be operated under the proper circumstances are shown in Figs. 9, 10, and 11 and will now be described. As shown in Fig. 9, a supporting plate 188 fastened to the vertical plate 147 carries the transformer 189, the tube 167, and the variable capacitor 178.

The base 148 carries the relay 168 and has fastened thereto a plate 190 (Fig. 11), to which the armature 191 of the relay is pivoted by means of a pair of clips as 192. The armature 191 has fixed thereto a retaining member 193 and a switch-operating member 194, which has adjacent one end thereof a set screw 195 providing an adjustable connection between the switch-operating member 194 and a plunger 196 slidable in the switch housing 197. One element of the switch 183 presses against the plunger 196 to maintain the plunger in engagement with the set screw 195. A spring 198 connected to the armature 191 and to the lower part of the plate 190 urges the armature clockwise about its pivot point.

The armature-retaining member 193 cooperates with a latch 199 pivoted on stud 200 on a sup-

porting plate 201 and urged clockwise, as viewed in Fig. 11, by a spring 202.

The operation of the parts associated with the relay is such that, when the relay 168 is operated, 5 the armature 191 is rocked counter-clockwise about the clips 192 and causes the switch-operating member 194 to close the switch 183 and the retaining member 193 to be moved downwardly to allow the latch 199 to rotate counter-clockwise and engage the retaining member 193 to maintain the armature in moved position and the switch 183 in closed position, even though the relay 168 is deenergized. The means for moving the latch 199 clockwise and releasing the armature 191 will be described later.

The switch 185, which is included in the circuit for the actuating electromagnet 146, is closed as long as the record material supporting means is in closed-throat position. As the actuating electromagnet 146 moves the supporting means to open-throat position, the switch 185 is opened and remains opened until the record material supporting means is moved back to closed-throat position. With this arrangement, the relay-operated switch 183 can be locked closed to maintain the operating circuit for the actuating electromagnet 146 to allow time for the magnet to operate, even though the control at the photoelectric cell 159 is only momentary, and the operating circuit can be broken at the switch 185 after the actuating electromagnet has performed its work. The means for controlling the opening and closing of the switch 185 are as follows.

The blades of the switch 185 normally tend 35 toward open position, but are held closed by a control member 211 pivoted on the bracket 151. The control member 211 is urged clockwise about its pivot by the tension of the switch blades and by a spring 212 fastened to the control member 211 and a supporting plate 213 (Fig. 9) carried by the bracket 151, but the control member is retained in the switch-closing position, as shown in Fig. 11, by a latch 214 pivoted on the supporting plate 213 and urged by a spring 215 into engagement with a projection 216 on the control member 211.

As explained earlier herein, the shaft 150 is rotated clockwise from the position shown in Fig. 11 when the record material supporting means is moved to open-throat position, either manually or by the electromagnet 146. Fastened to the shaft 150 by set screws is a two-armed lever 217, and, as the shaft 150 rotates, one arm 218 of the lever 217 engages the latch 214 and releases the control member 211, which allows the switch 185 to open. The other arm 219 of the lever 217 has a pin 220 therein, which engages a restoring extension 221 on the control member 211 to rock the control member counter-clockwise, as viewed in Fig. 11, to reclose the switch 185 when the shaft 150 is restored to the position shown in Fig. 11 as the record material supporting means is moved to closed-throat position.

65 The two-armed lever 217 is also used to operate a releasing means for the armature latch 199. The releasing means comprises a resilient member 222, which is slidable in the support 223 and has one end bent over to form a hook 224 operable to engage a projection on the latch 199 and rock the latch 199 clockwise to release the armature 191. Near the hooked end of the resilient member is a lateral projection 225, which cooperates with a curved plate 226, carried by the bracket 151, to guide the hooked end of the mem-

ber 222. The releasing means operates as follows. As the shaft 150 rotates clockwise when the record material supporting means are moved to open-throat position, the pin 220 moves to the left (Fig. 11) and advances the hook 224 past the latch 199, the projection 225 riding over the curved plate 226 and dropping off before the end of the movement. When the shaft 150 is restored to the position shown in Fig. 11 by moving the record material supporting means to closed-throat position, the pin 220 will shift the resilient member 222 to the right, and the projection 225 will cooperate with the under side of the curved plate 226 and insure that the hook 224 will engage the projection on the latch 199 and rock the latch clockwise to release the armature 191 and prepare the control means for another operation under control of the photo-electric cell.

The switch 187 (Figs. 10 and 12) in the operating circuit for the actuating electromagnet 146 is provided to prevent the operation of the magnet while the printing mechanism of the accounting machine is operating, to insure that if the beam of light is blocked from the photo-electric cell during an operation of the accounting machine, the actuating electromagnet 146 will not be energized to move the record material supporting means to open-throat position until the completion of the operation of the printing mechanism.

As explained earlier herein, the plate 72 associated with the accounting machine has a shaft 73 journaled therein, which shaft is driven one revolution counter-clockwise each time the accounting machine is operated. Pivoted on the plate 72 is a lever 227 carrying a roller 228, which is urged by a spring 229 into engagement with a cam 230 fast to the shaft 73. The lower end of the lever 227 has a link 231 pivoted thereto and urged clockwise by a torsion spring 232 to engage a tooth-like projection 233 thereon with a similar projection 234 on a pivoted member 235.

Whenever the accounting machine is not operating, the parts are in the positions as shown in Fig. 10, where the projection 233, bearing on the projection 234, has rocked the pivoted member 235 clockwise until the stop 236 on the member 235 engages a lower limiting finger 237, at which time the pivoted member has moved the blade of the switch 183 to close said switch. Just as soon as the accounting machine begins to operate, the high point of the cam 230 moves away from the roller 228 and allows the lever 227 to shift the link 231 to the right as viewed in Fig. 10. This will move the projection 233 to the right, and, as the stop 236 is in engagement with the finger 237, the projection 233 will ride over the projection 234 on the pivoted member 235 and press against the right-hand side of the projection 234, which will shift the pivoted member 235 counter-clockwise until the stop 236 engages an upper limiting finger 238 and the switch is opened. The high point of the cam 230 is so located relatively to the roller 228 and the projection 233 is so located relatively to the projection 234 that the pivoted member 235 is shifted to open the switch 187 almost simultaneously with the initiation of the accounting machine operation. After the printing has been accomplished, the cam 230 will cause the link 231 to move to the left and the projection 233 to ride over the projection 234 and bear upon the left-hand side of the projection 234 to rock

the pivoted member 235 clockwise to close the switch 187.

It is clear, therefore, that because of the operation of the switch 187, the photo-electric control means can cause the actuating electromagnet 146 to shift the record material supporting means to open-throat position during an operation of the accounting machine only after the printing part of the operation has been completed.

Obvious variations can be made in the control circuits without departing from the invention. The type of radiant energy used is described as light, but the invention is not to be limited to the use of light, as other forms of radiant energy could be used together with appropriate means for detecting the beam. Inasmuch as the critical location of the source of energy and the detector is such that the beam between them can be broken under proper circumstances, these elements may be used with a record material supporting means that has no lateral travel, or, if a traveling carriage is used, these elements may both be carried by the carriage, or one may be carried by the carriage and one may be stationary, without departing from the purpose of the invention.

Further, the control means and the actuating means are shown for causing the movement of the frame and the record material supporting means from closed-throat position to open-throat position, but it is clear that such a control could readily be utilized to cause the record material supporting means to be moved from open-throat position to closed-throat position.

Additional record material supporting means

Also associated with the platen 74 (Figs. 3, 4, and 5) is a second record material supporting means to guide and hold a second form of record material which is fed from the rear of the machine. The record material is fed from the rear of the machine by operation of the knobs 241 to rotate the platen clockwise, and also by the usual line-spacing mechanism (not shown). The second record material supporting means is rockable with the record material supporting frame and comprises sets of upper pressure rollers 242 and lower pressure rollers 243, which cooperate with the platen 74 to hold record material thereon, and an upper work table 244, which, with the guide plate 245 and the side guides 246 (Fig. 6) and 247, guide the record material to the platen from the rear of the machine.

A pair of brackets 248 and 249 are fastened to the side plates 80 and 81, respectively, of the rockable frame, and these brackets have pivoted thereon arms 250 and 251 connected by a rod 252, which carries the sets of upper pressure rollers 242. Springs 253 and 254 are connected to the arms 250 and 251 and to the brackets 248 and 249, respectively, and urge the pressure rollers 242 into engagement with the platen 74. Also pivoted on the brackets 248 and 249 are arms 255 and 256, respectively, which have fastened to their rear ends the upper work table 244 and at their front ends are connected by a spring 257, which rotatably supports the sets of lower pressure rollers 243.

The front edge of the upper work table 244 is cut out opposite the pressure rollers 243. Intermediate the rollers, this edge is curved to embrace the spring 257 and form a support for this spring intermediate the arms 255 and 256. Springs as 258 (only one shown) are fastened to the rear end of the arms 255 and 256 and to

the side plates 80 and 81 and urge the pressure rollers 243 into engagement with the platen 14.

The guide plates 245 are carried by the tie rod 83 and the shaft 112 and serve to guide the record material to and from the pressure rollers 242 and 243. The side guides 246 and 247 are adjustably supported on the upper work table 244 and control the lateral positioning of the record material thereon.

This additional record material supporting means is rocked with the frame, but does not release the record material when the frame is rocked. A pair of cams 259 and 260 are fastened on a sleeve 261 rotatable on a shaft carried by the side plates 80 and 81, which cams cooperate with rollers 262, 263, 264, and 265 on the arms 250, 251, 255, and 256, respectively, to separate the forward ends of these arms and move the pressure rollers from engagement with the platen. Counter-clockwise movement of the handle 266 causes the high points on the cams 259 and 260 to move opposite the rollers on the arms and move the pressure rollers to release the record material.

This additional record material supporting means, which is not released when the frame is moved to open-throat position, can be used to hold a journal sheet and superimposed carbon sheet in place to record data on said journal sheet as the data is recorded on a plurality of the ledger sheets which are inserted from the front of the machine in a plurality of operations.

SUMMARY

From the above description it is clear that the improved actuating means and control means simplify the operation of the machine, as compared with the known machines of the prior art, because they are faster in operation and require no accurate setting of control elements or any special operation of the machine to cause the supporting means to shift to open-throat position.

The actuating means makes the operation of the machine more flexible, because the operator of the machine can very quickly cause the record material supporting means to move to open-throat position to enable the material to be removed before any accounting machine operation takes place or after any number of amounts or other data have been recorded in one or more columns on the record material. All that is required is that the operator reach for the record material and in so doing interrupt the beam of light to cause the supporting means to shift to open-throat position.

The actuating means makes the operation of the machine more flexible, because the operator of the machine can very quickly cause the record material supporting means to move to open-throat position to enable the material to be removed before any accounting machine operation takes place or after any number of amounts or other data have been recorded in one or more columns on the record material. All that is required is that the operator reach for the record material and in so doing interrupt the beam of light to cause the supporting means to be shifted. Since, with any "front-feed" type of record material supporting means, the operator must remove and insert record material therein, the use of this necessary act without any additional effort on the part of the operator also to cause the throat to open will effect a considerable saving in time and effort if many record sheets are to be handled, as in the case given above, in which

75 daily balances are made on individual ledger sheets.

Because the actuating means operates so quickly, protective means are provided to delay the operation of the actuating means until after the printing means has operated if the beam of light is interrupted during an accounting machine operation and before the printing means has completed its operation.

10 The novel actuating means is also further prevented from performing idle operations when the record material supporting means is in open-throat position, so that repeated interruptions of the beam of light by the operator in removing and inserting record material will have no effect to 15 cause unnecessary operations of the actuating means.

A copending application of George Ramsey, Serial No. 380,158, filed February 24, 1941, shows a photo-electric cell and source of light located adjacent a shiftable record material supporting means for controlling the operation of the shifting means, as in the instant application, and said Ramsey application contains the broad claims to the photo-electric cell control of the shifting of the supporting means, whereas the claims of the instant application are drawn to a form of actuating means for shifting the supporting means under photo-electric cell control which is not shown in the Ramsey application.

20 While the form of mechanism herein shown and described is admirably adapted to fulfill the objects primarily stated, it is to be understood that it is not intended to confine the invention to the one form or embodiment herein disclosed, 25 for it is susceptible of embodiment in various forms all coming within the scope of the claims which follow.

What is claimed is:

40 1. A front-feed machine of the class described having front-feed means including a platen for receiving and holding a work sheet in front-fed position relative to said platen, said front-feed means being movable from a closed-throat or work sheet holding position to an open-throat or releasing position and vice versa; a photo-electric means; an electric lamp arranged so as to produce a light beam in front of the front-feed means; and a circuit having electromagnetic operating means therein to actuate the front-feed means to move the latter from a closed to open-throat position, said circuit being normally ineffective, but rendered effective upon interruption of the light beam whereby the front-feed means is moved to open-throat position to permit the removal of one work sheet and the insertion of another.

45 2. In a machine for making records on record material inserted from the front of the machine, the combination of record material supporting means including elements shiftable from closed-throat position to open-throat position and vice versa; means to shift said supporting means from closed-throat to open-throat position; means including an electromagnet for actuating said shifting means; an operating circuit for said electromagnet, said circuit including a plurality of switches; control means for closing one of said switches to complete the circuit; means settable according to the closed-throat or open-throat position of said supporting means; and means controlled by said settable means when set according to an open-throat position of the supporting means to open another of said plurality of switches 70 to prevent an operation of the electromagnet

when the supporting means is in open-throat position even though the control means closes said one switch.

3. In a recording machine, the combination of a record material supporting means comprising elements shiftable from closed-throat position to open-throat position and vice versa; means for shifting said supporting means from closed-throat to open-throat position; means including an operating electromagnet for actuating said shifting means; means mounted adjacent said supporting means and operable to produce and direct a beam of light across in front of the supporting means; a photo-electric cell; and a relay controlled by said photo-electric cell for causing the energization of the electromagnet each time the light is blocked from said photo-electric cell.

4. In a machine for making records on record material inserted from the front of the machine, the combination of record material supporting means including elements shiftable from closed-throat position to open-throat position and vice versa; means to shift said supporting means from closed-throat position to open-throat position; means including an electromagnet for actuating said shifting means; an operating circuit for said electromagnet; means for producing and directing a beam of light across the supporting means and in front thereof; a photo-electric cell upon which the beam of light is directed; means controlled by said photo-electric cell for completing said operating circuit when the beam is blocked from said cell; and means for retaining the operating circuit completed until the electromagnet has operated, even though the beam is no longer blocked from the cell.

5. In a machine for making records on record material inserted from the front of the machine, the combination of record material supporting means including elements shiftable from closed-throat position to open-throat position and vice versa; means to shift said supporting means from closed-throat position to open-throat position; means including an electromagnet for actuating said shifting means; an operating circuit for said electromagnet; means for producing and directing a beam of light across the supporting means and in front thereof; a photo-electric cell upon which the beam of light is directed; means controlled by said photo-electric cell for completing said operating circuit when the beam is blocked from said cell; means for retaining the operating circuit completed until the electromagnet has operated to move the supporting means to open-throat position, even though the beam of light is no longer blocked from the cell; and means settable according to the open-throat or closed-throat position of the supporting means and operable, when set according to the closed-throat position, to release said retaining means.

6. In a machine for making records on record material inserted from the front of the machine, the combination of record material supporting means including elements shiftable from closed-throat position to open-throat position and vice versa; means to shift said supporting means from closed-throat to open-throat position; means including an electromagnet for actuating said shifting means; an operating circuit for said electromagnet, said circuit including a plurality of switches; means for producing and directing a beam of light across in front of said supporting means; a photo-electric cell upon which the beam of light is directed; means controlled by said photo-electric cell for closing one

of said switches when the beam of light is blocked from said cell; means for retaining said one switch closed until the electromagnet has had time to operate the actuating means; means settable according to the open-throat or closed-throat position of said record material supporting means; means controlled by said settable means to open another one of said switches when the supporting means is shifted to open-throat position and to close said other one of the switches when the supporting means is shifted to closed-throat position; and means operated by said settable means for releasing the retaining means for said one switch when the supporting means is shifted to closed-throat position.

7. In a machine for making records on record material inserted from the front of the machine, the combination of record material supporting means including elements shiftable from closed-throat position to open-throat position and vice versa; means to shift said supporting means from closed-throat to open-throat position; means including an electromagnet for actuating said shifting means; an operating circuit for said electromagnet, said circuit including a plurality of switches; control means for closing one of said switches to complete the circuit; means to retain said one switch in closed position until after said electromagnet has operated; timing means operated during a recording operation; and means operated by the timing means to open another one of said plurality of switches to delay the operation of the electromagnet while a record is being made on said record material.

8. In a machine for making records on record material inserted from the front of the machine, the combination of record material supporting means including elements shiftable from closed-throat position to open-throat position and vice versa; means to shift said supporting means from closed-throat to open-throat position; actuating means for said shifting means, comprising an electromagnet, a member attracted to said magnet each time it is energized, and means connecting the member to the shifting means; a source of electricity; a circuit connecting said electromagnet to the source of electricity, said circuit including a normally closed switch and a normally open switch; means for producing and directing a beam of light in front of said supporting means; a photo-electric cell upon which said beam of light is directed; said means for producing the beam of light and said photo-electric cell being so located that the operator in reaching for the record material will interrupt the beam of light; relay means operated under control of said photo-electric cell each time the beam of light is interrupted, said relay means closing said normally open switch to cause the electromagnet to be energized and shift the supporting means to open-throat position; and means operated by the member for opening the normally closed switch when the electromagnet is energized.

9. In a machine for making records on record material inserted from the front of the machine, the combination of record material supporting means including elements shiftable from closed-throat position to open-throat position and vice versa; means to shift said supporting means from closed-throat to open-throat position; means including an electromagnet for actuating said shifting means; a circuit for energizing said electromagnet; control means for closing said circuit to cause said electromagnet to operate

the actuating means to shift the record material supporting means to open-throat position; means to restore the record material supporting means to closed-throat position and the actuating means to a position for operation by said electromagnet; and means operated by the actuating means, as the actuating means is operating to shift the supporting means to open-throat position, for opening the circuit to said electromagnet, and operated by said actuating means, as the actuating means is restored when the supporting means are returned to closed-throat position, for reclosing the circuit to said electromagnet, whereby unnecessary operations of the actuating means with the supporting means in open-throat position are prevented.

10. In a machine for making records on record material inserted from the front of the machine, the combination of record material supporting means including elements shiftable from closed-throat position to open-throat position and vice versa; means to shift said supporting means from closed-throat to open-throat position; means including an electromagnet for actuating said shifting means; an operating circuit for said electromagnet; a switch for closing said circuit; means for producing and directing a beam of light across in front of said supporting means; a photo-electric cell upon which the beam of light is directed; a relay operated under control of said photo-electric cell each time the beam of light is blocked from said cell, said relay having an armature movable to close said switch when the relay is operated; a latch for retaining the armature in moved position to hold said switch closed and prevent the photo-electric cell from further controlling the actuating means; means for releasing said latch; and means operated by the supporting means, when they are moved to closed-throat position, for operating said releasing means and restoring the actuating means to the control of the photo-electric cell.

11. In a recording means having printing means for making records on record material introduced from the front of the machine, the combination of record material supporting means including elements shiftable from closed-throat position to open-throat position and vice versa; means to shift said supporting means from closed-throat position to open-throat position; means including an operating electromagnet for actuating said shifting means; an operating circuit for said electromagnet, said circuit including a normally open switch and a normally closed switch; means for producing a beam of light; a photo-electric cell engageable by said beam of light; a relay energized under control of said photo-electric cell when the beam of light is blocked from said cell; an armature associated with said relay and operable to close the normally open switch when the relay is energized; means for retaining the armature in operated position to maintain the switch in closed position; means operable to open the normally closed switch while the printing means is functioning during an operation of the recording machine; and means for releasing the latch after the electromagnet has operated, the control of said switches being so coordinated that a momentary blocking of the light from the photo-electric cell at any time will cause the electromagnet to operate the shifting means to shift the supporting means to open-throat position immediately, except when the printing means is operating, and

then the shifting is delayed only until the printing is completed.

12. In a recording machine having printing means for making records on record material introduced from the front of the machine, the combination of record material supporting means including elements shiftable from closed-throat position to open-throat position and vice versa; means to shift said supporting means from closed-throat to open-throat position; means, including an operating electromagnet, for actuating said shifting means; an operating circuit for said electromagnet, said circuit including a normally open switch and a pair of normally closed switches; means for producing a beam of light; a photo-electric cell engageable by said beam of light; a relay energized under control of said photo-electric cell whenever the beam is blocked from said cell; an armature operated by said relay to close said normally open switch when said relay is energized; a latch cooperable with the armature to retain the armature in operated position and the normally open switch in closed position; means operable to open one of the normally closed switches while the printing means is functioning during an operation of the recording machine; mechanism operated by the electromagnet to open said other normally closed switch when the actuating means operates the shifting means to move the supporting means to open-throat position; means to restore the supporting means to closed-throat position and the mechanism and actuating means to unoperated position, said mechanism restoring said other normally closed switch to closed position; and means operated by said mechanism, as it is restored, for releasing said latch, the control of the operation of the electromagnet being such that the electromagnet can operate the actuating means at any time when the record material supporting means is in closed-throat position and the printing means is not being operated during a recording machine operation.

13. In a recording machine for making records on record material inserted from the front of the machine, the combination of record material supporting means including elements shiftable from closed-throat position to open-throat position and vice versa; means to shift said supporting means from closed-throat to open-throat position; means, including an electromagnet, for actuating said shifting means; means for supplying potential for operating said electromagnet; a circuit connecting said electromagnet directly with said supply means, said circuit containing a normally open switch; means for producing a beam of light; a photo-electric cell engageable by said beam of light; said means for producing the beam of light and said photo-electric cell being so located in front of the supporting means that the beam will be broken when the operator reaches for the record material; and means controlled by said photo-electric cell for closing the switch whenever the beam is broken to thereby cause the electromagnet to operate the shifting means and immediately move the supporting means to open-throat position whether or not the recording machine has been operated one or more times.

14. In a recording machine having printing means for making records on record material inserted from the front of the machine, the combination of record material supporting means including elements shiftable from closed-throat position to open-throat position and vice versa;

means for shifting said supporting means from closed-throat to open-throat position; means, including an operating electromagnet, for actuating said shifting means; means providing a source of current for operating the electromagnet; a circuit connecting the electromagnet to said means providing the source of current and including a normally open switch and a normally closed switch; means for producing and directing a beam of light in front of said supporting means; a photo-electric cell upon which said beam is directed; means controlled by said photo-electric cell and operable to close said normally open switch and cause said electromagnet to actuate said shifting means when the beam of light is blocked from said cell as the operator reaches for the record material; means to retain the normally open switch in closed position until the electromagnet has operated; delay means operated by said recording machine to open the normally closed switch during the operation of the printing means, the control of said switches being such that the normally open switch can be closed to cause the electromagnet to operate and move the supporting means to open-throat position at any time regardless of whether or not the recording machine is operating or has been operated, the delaying means only operating to open the normally closed switch for that part of a recording machine operation to delay the shifting of the supporting means until the printing means has functioned if the normally open switch is closed during an operation of the recording machine.

15. In a machine for making records on record material inserted from the front of the machine, the combination of record material supporting means including elements movable from a record material retaining condition to a record material releasing condition and vice versa; means to move the movable elements from record material retaining condition to record material releasing condition; driving means for actuating the mov-

ing means; a circuit for controlling the operation of the driving means; means for producing and directing a beam of light across the supporting means and in front thereof; a photo-electric cell upon which the beam of light is directed; means controlled by said photo-electric cell and operated to complete said circuit when the beam is blocked from said cell; and means for retaining the last-mentioned means in operated position until the driving means has operated the moving means, even though the beam is no longer blocked from the cell.

16. In a machine for performing operations which may include the making of records on record material inserted from the front of the machine, the combination of record material supporting means, including elements movable from record material retaining condition to record material releasing condition and vice versa; moving means to move said elements from record material retaining condition to record material releasing condition; driving means for actuating the moving means; means operable to initiate an operation of the driving means; means to retain the operation-initiating means in operated condition until the driving means has actuated the moving means; timing means operated by the machine when the machine is operating to perform an operation; and means operated by the timing means, when the timing means is operated by the machine, to delay the initiation of the operation of the driving means; the control of the driving means being such that the operation of the initiating means will cause the driving means to actuate the moving means to move said elements to record releasing condition immediately, except when the machine is operating, and then the initiation of the operation of the driving means is delayed until after a predetermined portion of the operation of the machine has been completed.
